UNITED STATES PATENT OFFICE.

JOSEPH CASTELLANA, OF NEW YORK, N. Y.

DESIGN FOR A STATUETTE.

Application filed June 14, 1924. Serial No. 9,875. Term of patent 14 years.

To all whom it may concern:

Be it known that I, JOSEPH CASTELLANA, a subject of the King of Italy, residing at New York, county of Bronx, and State of New York, have invented a new, original, and ornamental Design for Statuettes, of which the following is a specification, reference being had to the accompanying drawing, forming part thereof.

I claim:

The ornamental design for a statuette as shown.

JOSEPH CASTELLANA.
